UNITED STATES PATENT OFFICE.

ROY D. BAER, OF LAKE VIEW, IOWA.

WAGON-BRACE.

1,200,913.

Specification of Letters Patent. Patented Oct. 10, 1916.

Application filed December 1, 1915. Serial No. 64,521.

To all whom it may concern:

Be it known that I, ROY D. BAER, a citizen of the United States, residing at Lake View, in the county of Sac and State of Iowa, have invented certain new and useful Improvements in Wagon-Braces; and I do hereby declare the following to be a full, clear, and exact description of the invention, such as will enable others skilled in the art to which it appertains to make and use the same.

The invention relates to improvements in wagon braces.

The object of the present invention is to improve the construction of wagon braces and to provide a simple, practical and comparatively inexpensive device of strong and durable construction adapted to be readily applied to a wagon box and capable of preventing the sides from spreading under the weight or strain of a load, and of supporting the side steps as well as serving as a means for connecting the sides with the bottom of the box.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing Figure 1 is a side elevation of a wagon provided with a pair of braces constructed in accordance with this invention, Fig. 2 is a transverse sectional view of the same, Fig. 3 is a detail perspective view of one end of one of the braces, Fig. 4 is a detail view illustrating the manner of securing the braces to the transverse cleats of the wagon box.

Like numerals of reference designate corresponding parts in the several figures of the drawing.

In the accompanying drawing in which is illustrated the preferred embodiment of the invention, 1 designates a wagon box provided with a pair of braces 2 constructed of angle iron and consisting of a body portion extending across the bottom 3 of the wagon box to a point beyond the sides 4 thereof and having inclined arms 5 extending upwardly and inwardly from the projecting

portions of the body of the brace to the upper portions of the sides of the wagon box and having upper terminals 6 bolted or otherwise secured to the said sides 4; the 60 terminals 6 are formed by extending one flange or wing of each end of the brace beyond the other flange or wing as clearly illustrated in Fig. 3 of the drawing. The projecting portions of the body of the brace 65 support the box steps 7 which are arranged between the wagon box and the upwardly inclined arms 5.

The body portion of the brace has its flanges or wings arranged in vertical and 70 horizontal planes and the horizontal flange or wing 8 is provided with perforations 9 for the reception of bolts 10 or suitable fastening devices for securing the box steps to the brace. The horizontal flange or wing 75 8 is also provided with perforations 11 adapted to receive the lower threaded terminal portions 12 of straps 13 which are secured to the sides of the wagon box. The vertical flanges or wings 14 of the body portion of the brace are secured by bolts 15 or other suitable fastening means to the adjacent transverse cleats 16 to which the floor or bottom of the wagon box is secured. The braces are adapted to prevent a wagon box 80 from spreading and being strained or otherwise injured when it receives a load and they are adapted to support the box step and also serve as means for attaching the lower ends of the box straps. Furthermore 85 the braces are secured to the transverse cleats of the wagon box and thereby serve to connect the sides with the bottom and increase the strength of the box and the durability of the same.

What is claimed is:

1. The combination with a wagon body provided at the bottom with transverse cleats, of a pair of braces extending across the lower face of the bottom of the box contiguous to the said cleats and composed of angle metal having wings or flanges, one of the wings or flanges of each brace being fitted against and secured to one of the said transverse cleats, said brace being extended beyond the sides of the wagon box, and provided with inclined arms extending upwardly and inwardly and having terminal attaching portions secured to the sides of the wagon box.

2. The combination with a wagon box provided at the bottom with transverse

cleats, of a pair of braces extending across the lower face of the bottom of the box contiguous to the said cleats and composed of angle metal having wings or flanges, one of the wings or flanges of each brace being fitted against and secured to one of the said transverse cleats, said braces being extended beyond the sides of the wagon box to form supports for the box steps, said braces being also provided with inclined arms extending upwardly and inwardly and having terminal attaching portions formed by extending

one of the wings or flanges beyond the other and secured to the sides of the wagon box and straps fastened to the sides of the wagon box and piercing the projecting portions of the braces. 15

In testimony whereof I affix my signature in presence of two witnesses.

ROY D. BAER.
